Primary Examiner — Caron D Veynar*Assistant Examiner* — Abraham Bahta(74) *Attorney, Agent, or Firm* — Winthrop & Weinstine, P.A.(57) **CLAIM**

The ornamental design for a flat bottom tapped pouch with tapered side gussets, as shown and described.

DESCRIPTION

FIG. 1 is a perspective view of the flat bottom tapped pouch with tapered side gussets showing my new design;

FIG. 2 is a front view thereof;

FIG. 3 is a rear view thereof;

FIG. 4 is a side view thereof;

FIG. 5 is another side view thereof;

FIG. 6 is a top view thereof; and,

FIG. 7 is a bottom view thereof.

The portions of the disclosure shown in broken lines form no part of the claimed design.
